UNITED STATES PATENT OFFICE.

AUGUSTINE DAVIS, OF CHICAGO, ILLINOIS, ASSIGNOR TO DAVIS ACETYLENE COMPANY, OF ELKHART, INDIANA, A CORPORATION OF SOUTH DAKOTA.

HOOD FOR DISCHARGE-PIPES OF GAS-GENERATORS.

No. 864,448.

Specification of Letters Patent.

Patented Aug. 27, 1907.

Application filed June 4, 1906. Serial No. 320,060.

To all whom it may concern:

Be it known that I, AUGUSTINE DAVIS, a citizen of the United States, residing at Chicago, in the county of Cook and State of Illinois, have invented certain 5 new and useful Improvements in Hoods for the Discharge-Pipes of Gas-Generators, of which the following is a specification.

My invention relates to an improved hood detachably secured to the end of the discharge pipe of a gas 10 generator, and is intended more particularly for use in acetylene generators of the character set forth in my Patent, No. 719,091, granted January 27, 1903. It has been found that hoods of this type become gummed up or fouled after having been in use some time; and 15 it is not only desirable, but quite necessary that they be cleaned occasionally. In order to accomplish this readily and easily I have invented such a hood which can be quickly removed from the discharge pipe to be cleaned and as readily replaced.

20 In the accompanying drawings, which form a part of this specification, and wherein like reference characters refer to the same parts throughout,—Figure 1 is a side view of such a hood attached to the end of the gas discharge pipe; Fig. 2 is a central longitudinal section 25 of the construction illustrated in Fig. 1; and Fig. 3 is a bottom plan view of the same.

The hood comprises a metallic casing 10 preferably flattened as illustrated, open at its bottom end, and provided at its top end with a plurality of minute perforations 11. Within this outer member 10 is a smaller inner hood 12 of similar cross-section, but of smaller 30 dimensions. Hood 12 is preferably secured to the outer hood, as illustrated in Fig. 2, by means of solder, and is closed at its upper end and provided at its 35 lower end with a perforated band or petticoat 13. Fastened to and projecting downwardly through the open mouth of hood 10 is a split cylindrical tube 14 soldered to hood 10 and provided along its split edges with a pair of outwardly extended flanges 15 apertured 40 at 16 to receive a bolt or screw 17 so that this tubular extension may be securely fastened to and encircle the upper end of a gas pipe 18, conducting the acetylene 45 gas from the generator.

When in the machine for generating gas, the hoods 45 10 and 12 are immersed in water to a height approximately that indicated by the line 19—19, so that a water-seal is secured. The gas, rising through the pipe 18, passes into the chamber or hood 12, displacing the water therein by forcing it downwardly out of its lower

open mouth and then the gas passes through the numerous perforations in the sleeve or petticoat 13, bubbling up through the water between the two hoods and eventually passing off to the gas reservoir or bell through the minute perforations 11 in the top of hood 10. By using a construction of this character, fluctuations in the generation of gas and the differences in pressure are not communicated to any extent to the mass of gas in the reservoir or bell. It will be apparent that by removing or loosening the bolt 17, thereby releasing the grasp of the tubular extension 14 upon 60 the end of pipe 18, the combined hoods may be pushed upwardly and removed from the pipe, so that they may be cleaned. In order to replace the hoods the extension 13 is merely held upon the pipe, the bolts 17 tightened, and the parts are then firmly held in place. 65

The construction described not only permits the hood to be readily removed for cleaning or other purposes without necessitating the removal of the gas discharge pipe 18, but it also permits the adjustment of the hood on said pipe so as to bring the water level in 70 the hood at any desired height. Heretofore, so far as I am aware, hoods of this character have been permanently secured to the gas discharge pipe, thus rendering adjustability of the hood impossible and necessitating considerable labor and trouble in getting at the 75 hood for cleaning purposes.

To those skilled in the art it will be apparent that minor mechanical changes may be made in the structure herein illustrated and described without departing from the substance of my invention or sacrificing 80 any of its advantages.

I claim:

1. In a device of the character described, the combination of a discharge gas pipe, a perforated hood fitted to the end of said discharge pipe, said hood having a split extension encircling the end of said pipe, and means to clamp said split extension to said pipe, substantially as described.

2. In a device of the character described, the combination of a discharge gas pipe, a perforated hood fitted to one end of said pipe, said hood having a split extension encircling the end of said pipe, said extension having outwardly extended flanges along the edges of its split portion, and a clamping bolt passing through apertures in said flanges to cause said extension to grasp said pipe 90 to retain said extension and hood in position thereon, substantially as described.

AUGUSTINE DAVIS.
